UNITED STATES PATENT OFFICE

164,966

TABOURET

William L. Snyder, New York, N. Y.

Application May 22, 1951, Serial No. 15,282

Term of patent 7 years

(Cl. D33—19)

To all whom it may concern:

Be it known that I, William L. Snyder, a citizen of the United States, residing at the city of New York, county of Queens, State of New York, have invented a new, original, and ornamental Design for Tabouret, of which the following is a specification, reference being had to the accompanying drawing, forming a part hereof.

Fig. 1 is a perspective view of my tabouret with the drawer and closet door closed;

Fig. 2 is a perspective view of my tabouret with the drawer and door partly opened.

The opposite side is similar to the side shown and the back is the same as the front shown.

I claim:

The ornamental design for a tabouret, substantially as shown and described.

WILLIAM L. SNYDER.
